UNITED STATES PATENT OFFICE.

EDGAR F. BROWN, OF SALISBURY, MARYLAND.

SPEED-GOVERNING DEVICE.

Application filed November 24, 1925. Serial No. 71,143.

This invention relates to improvements in a mechanism for automatically controlling the speed of an internal combustion engine.

An object of the invention resides in providing a device for governing the speed of an internal combustion engine including a pair of disk members interposed in the driving connection between the internal combustion engine and the driven shaft, adapted for a relative movement, together with means for maintaining the disks in a predetermined relation when no load is applied to the driven shaft while the application of a load to the driven shaft rotates the disks relative to one another in a predetermined amount, which relative movement is employed for operating a throttle control mechanism in order to prevent the motor from racing under no load conditions and for opening the throttle to permit the operation of the engine at a predetermined maximum speed when a load is applied to the shaft.

A further object of the invention is to provide a pair of disk members adapted for relative movement of a predetermined character which are normally retained in one limit position by spring operated wedge mechanism under no load condition and which are moved to another predetermined position when the load is applied to the driven shaft, overcoming the action of the spring, the motion of the wedge mechanism being utilized for the purpose of controlling the speed of the motor through the throttle to prevent racing of the motor under no load conditions.

The invention comprehends numerous other objects residing in the details of construction and association of the parts of the apparatus which are more particularly pointed out in the following detailed description and claim directed to a preferred form of the invention, it being understood however, that various changes may be made in the size, shape and relation of the parts without departing from the spirit and scope of the invention as herein set forth.

In the drawing forming part of this application:

Figure 1 is a side elevation showing portions in section of the improved coupling and control device applied between an internal combustion engine and a generator.

Fig. 2 is a detail sectional view taken on the line 2—2 of Fig. 1.

Fig. 3 is a view similar to Fig. 2 showing the disks in the opposite limits of movement from that shown in Fig. 2.

Fig. 4 is a sectional view taken on line 4—4 of Fig. 1.

An internal combustion engine of any conventional form is indicated at 1, having the crank shaft 2, while an electric generator is indicated at 3 and a driven shaft 4 forming the armature shaft of the generator.

The present invention is designed for use more particularly with an internal combustion driven generator structure generally used as part of portable arc welding units, and provides a coupling device between the motor and generator as well as an automatic control for the speed of the motor.

This invention includes an annular driving disk 5, a hub portion 6 secured to the crank shaft of the motor to which is secured a driven disk 7 having a hub portion 8 mounted on the driven shaft 4. A driving connection between the driving and driven disks 5 and 7 respectively is formed by the bolt connections 9 at diametrically opposite points adjacent the periphery of said disk and the driven disk is formed with slotted openings receiving said bolts 9 in order to permit a relative rotative movement of the driven disk with respect to the driving disk.

At intermediate diametrically opposed points from bolts 9, the driven disk 7 is formed with a pair of arcuate slots 11 in which are mounted stud bolts 12 rigidly secured and mounted on the driving disk 5. The end portions of these stud bolts 12 within the slots 11 are formed with beveled faces 13 as clearly shown in Figs. 2 and 3 with which engage the beveled faces 14 of the rod members 15 mounted in the arms 16 formed on the annular body member 17 slidably mounted on the shaft 4 and having a recessed end portion receiving the end of the hub 8 as indicated at 18 in Fig. 1.

A flanged collar 19 is mounted on the driven shaft 4 in spaced relation to the body 17 and between the body and the flanged collar 19 is mounted a coiled spring 20 surrounding the driven shaft 4 and normally under compression for forcing said body toward the driving and driven disks 5 and 7 respectively.

The cylindrical body 17 is formed with an annular channel 21 in which is positioned the forked end 22 of the control lever 23 pivotally mounted in the bracket 24 secured 5 to the body of the generator 3, while the free end is connected by a rod 25 to the throttle lever 26 of the motor.

In operating a motor generator set of this character, in an arc welding set, the motor 10 under load is usually operated to drive the generator during the welding operation, which places a substantial load on the generator at a speed of approximately 1,200 R. P. M., while it is desirable to have the 15 motor merely idle at a relatively low speed of usually about 600 R. P. M. when the load on the generator is released. It is therefore necessary to provide a governor for the motor to prevent the same from racing 20 under no load conditions and it has been found in practice that the usual weight operated centrifugal governor does not operate efficiently in controlling the motor so that when the same is idling and a load is applied 25 to the generator, the motor will gain sufficient speed to operate the generator at the proper speed for the welding operation within a reasonable length of time. It has been found by actual practice that with a 30 centrifugal governor as above mentioned, the motor will decrease in speed from the idling speed for a period of several minutes before it will begin gaining speed upon the application of a load to the generator. As 35 a result, it places the operator or welder at a substantial inconvenience in welding with an apparatus of this character in view of the fact that the operation of the welding tool at low speed of the generator produces 40 undesirable results in the materials to be welded.

The present invention overcomes these difficulties and provides a substantially simple and quickly responsive mechanism to 45 load and no load conditions on the generator.

The driving and driven disks 5 and 7 provide a direct driving connection between the crank shaft and the driven shaft 4, which have a limited rotative movement with respect to one another by the slotted structure of the driven disk by the slotted disk as above described. The driven disk is normally retained in the position illustrated in Fig. 2 due to the action of the coiled spring 50 55 20 in moving the body 17 toward the driven disk which forces the beveled end 14 of the rod 15 into the slots 11 and thru the cooperation of the beveled faces 13 and 14, the body 17 will have a slight rotative movement with respect to the hub 6 of the driving disk so that the driven disk will be normally retained in the position shown in Fig. 2. In this position of the parts, the control 23 will operate the throttle lever 26 60 65 so that the throttle of the internal combus-

tion engine will be moved to cut off the intake to the engine to such a point as to reduce the speed to a point as above described, so that the motor will not race under no load conditions.

With the mechanism operating in this manner, the use of the generator for welding which will immediately apply a load on the driven shaft 4 by throwing a substantial current from the generator through the output circuit thereof will cause a substantially greater force to be applied to the driven disk 7 having a tendency to prevent its rotation with the disk 5 in the direction of the arrow in Fig. 3 as a result of which the disk 7 will rotate relative to the disk 5 so that the rod 15 will be forced outwardly from the recesses 11 to the position shown in Fig. 3. This operation takes place immediately upon the application of the load to the generator and the movement of the body 17, effected by the operation of the disk 7 will operate the lever 23 and through the rod connection 25 will move the throttle 26 to a substantially open position, which will permit the application of greater power and the admission of more fuel to the motor as a result of which it will immediately increase speed to approximately the speed above described for the operation of the generator for welding purposes.

It will thus be seen that the driving connection between the motor and generator is directly through the disks 5 and 7 and the bolt connections 9 as well as the stud bolts 100 12, and in which the body 7 is movable axially on the shaft and hub 8 through the action of the spring 20, is not subjected to the driving strain and power transmitted between the motor and generator but is 105 adapted for sufficient longitudinal movement on the shaft to operate the lever 23 for the control purposes desired. It will also be understood that the spring 20 is of such a character that the release of loads on 110 the driven shaft 4 which allows the shaft to be substantially free of resistance of rotation with the disk 5 permits the spring 20 to move the disks from the position of Fig. 3 to the position shown in Fig. 2 where- 115 in the same is retained under normal no load condition.

Having thus described my invention, what I claim as new is:—

In a speed governing device of the class 120 described, a pair of discs disposed in meeting contact, one disk being adapted to be mounted upon a driving shaft and the other disk being adapted to be mounted upon a driven shaft, said last named disk being provided 125 with a plurality of elongated slots, the other disk being equipped with circumferentially spaced bolts, certain ones of which extend through complementary slots to provide a driving connection between the disks, said 130

driving connections permitting relative circumferential movement of the disks, certain of said bolts being provided with heads located in the remaining slots, said heads having bevelled faces, a body slidably mounted upon the driven shaft, a spring cooperating with said body to move it in a direction toward said disks, and projections carried by said body and including beveled ends engageable with the bevelled faces on said heads.

In testimony whereof I affix my signature.

EDGAR F. BROWN.
